UNITED STATES PATENT OFFICE.

JOHN ALONZO WARD, OF SHARPSVILLE, ASSIGNOR OF ONE-HALF TO.
WILLIAM V. BYARD, OF SHARON, PENNSYLVANIA.

TOY.

SPECIFICATION forming part of Letters Patent No. 295,845, dated March 25, 1884.

Application filed January 24, 1884. (No model.)

To all whom it may concern:

Be it known that I, JOHN A. WARD, a citizen of the United States of America, residing at Sharpsville, in the county of Mercer and State of Pennsylvania, have invented certain new and useful Improvements in Toys; and I do hereby declare the following to be a full, clear, and exact description of the invention, such as will enable others skilled in the art to 50 which it appertains to make and use the same, reference being had to the accompanying drawings, and to letters or figures of reference marked thereon, which form a part of this specification.

15 My invention has reference to toys; and it consists in the improved structure hereinafter described and set forth.

In the accompanying drawings, Figure 1 is a side elevation, a portion being removed. 20 Fig. 2 is a plan view, illustrating the parts arranged for storage or transportation, and Fig. 3 is a cross-section on the line 1 2 of Fig. 1.

The toy consists, principally, of the representation of a man aiming a gun, and detachably mounted on the base of a case, together 25 with spring devices for causing a plunger or rod to be moved violently forward in the gun-barrel, and project any rod or ball that may have been previously inserted in said barrel.

30 Combined with the above and adapted to be erected at varying points on the cover of the case, in advance of the figure above described, is a standard carrying detachably a target-disk and a pivoted bird, designed when struck, 35 to be forced back into a recess formed in the standard.

A represents the case, the bottom *a* of which is provided at one end with a block, *b*, centrally dovetailed, as illustrated in Fig. 3, to 40 engage the dovetailed base *c* of the figure B, and maintain the same in position, as shown in Fig. 1. A thumb-screw, *q*, is located on the dovetailed base, and when turned engages with the bottom of the base to lock the figure B 45 rigidly in position. The upper portion of the figure is cut away, as shown in Fig. 1, to contain a pivoted bell-crank lever, *d*, secured by a pivot-bolt, *e*, which also secures the other section, *C*, of the figure in position, as shown

in Fig. 3. The barrel or tube *D* is provided 50 at its rear end with an ear, *f*, perforated for its attachment to the projection *g* of the figure, which projection exteriorly represents the stock and hands holding the same. The forward end of the bell-crank lever *d* is looped to 55 engage the hooked end *h* of a rod, *E*, the forward end, *i*, of which is headed, as shown in dotted lines, Fig. 1. A contracting spring, *j*, connecting with the loop portion of the bell-crank lever and with a pin, *k*, on the projection *g*, normally tends to maintain the headed portion *i* of the rod *E* in the forward part of 60 the barrel. The other member, *l*, of the bell-crank lever is bent, as illustrated in Fig. 1, so that its end projects through a vertical slot 65 formed between the upper portion of figure B and the section C. The spring traction on the bell-crank is limited by the upper end of rod *l* coming in contact with that portion of the figure B forming the top *m* of the slot. The 70 cover *F*, sliding longitudinally in grooves formed in the sides of the box *A*, has pivotally secured on its upper side a bar, *G*, provided with a series of perforations, one of 75 which is adapted to receive the tapered end of a standard, *H*, the upper part of which is enlarged to form a recess, *n*. At the upper front corner of the standard is pivotally secured the representation *o* of a bird. A target-disk, *p*, is pivotally mounted at the rear 80 upper corner of the standard behind the figure *o*.

The operation of the device will be readily understood. When a small rod or ball is placed in the gun-barrel and the member *l* of the bell-crank lever is depressed, the said bell-crank lever is tilted on its pivot and distends the spring *j* and likewise draws back the headed rod *E*. When pressure is removed from the member *l* the spring *j* quickly moves 85 the bell-crank lever to its first position, and rapidly moving the rod *E* forward in the barrel expels the projectile against the target. If the figure *o* is struck it will be tilted backward on its pivot, and drops out of sight into the 90 recess of the standard. The bar *G* may be 95 swung on its pivot to occupy the positions shown both by dotted and full lines, Fig. 1, so

as to increase or decrease the distance from the figure B in which the various adjustments may be made in the perforations of the said bar. By longitudinally withdrawing the dove-tailed portion *c* of the figure B from the recess in the block *b*, and by moving the figure *o* back into the recess of its standard, and removing the target - disk from said standard, and the standard from the bar G, the parts 10 may be readily arranged in the box, as shown in Fig. 2, and the same closed.

I claim—

1. The combination, in a toy, of a figure, B, detachably mounted in position and provided 15 with devices for projecting objects, and a standard carrying a target and detachably mounted in position, substantially as set forth.

2. The combination, in a toy, of a box, a figure, B, detachably mounted in said box and 20 provided with mechanism for projecting objects, and a standard carrying a target and detachably mounted in the cover of the box, substantially as set forth.

3. The combination, in a toy, of a box, a figure, B, provided with a dovetailed base adapted 25 to engage a dovetailed recess in the box-bottom, a device for locking said base in position, mechanism combined with said figure for projecting objects, and a target detachably mounted in position, substantially as set forth.

4. The combination, in a toy, of a box, a figure, B, detachably mounted in position and provided with means for projecting objects, and a standard carrying a target and mounted in a rod provided with a series of recesses and piv- 35 otally secured to the cover of the box, substantially as described.

5. The combination, in a toy, of the figure B, detachably mounted in position and provided with means for projecting objects, a standard mounted in position and provided with a recess in its upper portion, and a piv- 40 oted figure, *o*, on said standard, substantially as set forth and described.

6. The combination, in a toy, of a figure, B, 45 detachably mounted in position and provided with a tube or barrel, D, a pivoted bell-crank lever having the projecting member *l*, a headed rod playing in the tube or barrel and connected to the bell-crank lever, and a spring connect- 50 ed, as described, to said bell-crank lever, substantially as set forth.

In testimony whereof I affix my signature in presence of two witnesses.

JOHN ALONZO WARD.
